UNITED STATES PATENT OFFICE.

CLAUDE SPENCER SYDENHAM, OF KILMARNOCK, SCOTLAND.

IGNITION APPARATUS OF GAS-ENGINES.

1,229,823.

Specification of Letters Patent. Patented June 12, 1917.

Application filed February 17, 1914. Serial No. 819,197.

To all whom it may concern:

Be it known that I, CLAUDE SPENCER SYDENHAM, a subject of the King of Great Britain and Ireland, and a resident of Kilmarnock, Scotland, electrician, have invented new and useful Improvements in Ignition Apparatus of Gas-Engines, of which the following is a specification.

This invention has reference to improvements in the ignition apparatus of gas engines, of the type having a stationary insulated electrode and a moving uninsulated electrode.

Hitherto with this type of ignition contacts usually employed in these engines and particularly when such are driven by suction gas, there has been a degree of uncertainty associated with their working.

According to the improvements of this invention the stationary electrode is insulated at its inner end by an insulating washer carried by a cup between which and the ignition plug asbestos or like packing is arranged so as to make a gas-tight joint, and a cup, which is formed with holes so as to ventilate the air space surrounding the stationary electrode so as to allow full scope for expansion and contraction of the dry air and thus overcome the objections of condensation of moisture which by saturation or capillary action destroys the insulating qualities of mica, carries the insulating washer at the outer end of the said electrode and this cup is also formed with an extended flange to act as a shield to protect the mica washer from oil splashings and other moisture which permeating the mica layers destroys the insulating properties of same, and a metal collar coated with porcelain, rust proof shellac or the like is arranged on the washer to minimize the probability of moisture setting on same.

In order that others skilled in the art to which my invention relates may properly understand same I have hereunto appended one sheet of explanatory drawings in which Figure 1 is a sectional elevation and Fig. 2 a plan view of ignition apparatus of gas engines as constructed according to the improvements of this invention.

Referring to these drawings:

In carrying the improvements of this invention into effect, or practice the mica washer 1 at the top of the stationary contact rod 2 is supported by a brass or gun metal journal or cup 3 arranged on the face of the

plug 4 around the opening 5 through which the rod 2 is passed. Holes 6 are formed through the cup 3 so as to efficiently ventilate the space or opening 5 and thus provide a dry and reliable insulation of rod 2. A steel collar 7 coated with porcelain, rust proof shellac or the like is mounted on the top of the mica washer 1 so as to minimize the probability of the condensation setting on the mica washer surface. The connection 8 from the magneto to the insulated rod 2 is fitted between nuts 9 at the upper end of the rod 2. A shield 10 for the washer 1 is formed by an extension of the flange of the cup 3.

The mica washer 12 at the lower end of the rod 2 is carried between a head 13 on said rod and a metal cup or holder 14. A gas tight joint is made between the cup 14 and the inner face of the plug 4 by the insertion of a ring 15 of asbestos, copper asbestos or other suitable material.

The spindle 16 and foot 17 of the moving contact are made in one piece and the operating crank or lever 18 which is fitted to the upper end of the spindle 16 on a square or rectangular part of same, preferably tapered, is preferably prevented from working slack on the spindle by means of a pinching screw 19 preferably not less than $\frac{1}{4}$ an inch passing through eye of crank 18 to bear on the square corner of spindle. The usual spring connection 20 is taken from a pin 21 on the crank 18 to a pin 22 secured in the plug 4.

The extra return contact 23 which is taken from the top of spindle 16 is preferably fitted between nuts 24, and this contact which consists of a stranded flexible steel or copper wire or the like has its other end metallically connected with metal frame of magneto, or some other convenient place on water jacket of engine, thus insuring perfect metallic contact throughout with consequent full pressure of current developed by magneto being arced between contact points with varying density.

What I claim and desire to secure by Letters Patent is:

1. In ignition apparatus the combination of a plug having a cavity; an oscillatory electrode in said cavity; with means including a bearing rotatably supporting the electrode and spaced away from the walls of the cavity, said bearing having in it a ventilating passage opening into said cavity.

2. In ignition apparatus the combination of a supporting structure having a cavity; an electrode extending therethrough; means for supporting said electrode including an insulating washer holding the electrode spaced away from the walls of the cavity in which it is mounted; and a structurally independent metal collar having a rust proof coating mounted on the insulating washer 10 surrounding but spaced away from the electrode.
3. In ignition apparatus the combination of a plug having an opening therethrough; an electrode passing through said opening; insulating washers adjacent each end of the electrode; with removable cup shaped journal members receiving the washers and engaging the plug in positions to hold the electrode spaced away from the walls of the 15 opening.
4. In ignition apparatus the combination of a plug having an opening therethrough; an electrode passing through said opening; insulating washers adjacent each end of the electrode; with cup shaped journals receiving the washers and engaging the plug in positions to hold the electrode spaced away from the walls of the opening; there being 20 ventilating passages through the walls of
- the outer journal opening into the space surrounding the electrode.
5. In ignition apparatus the combination of a plug having two openings therethrough; an uninsulated electrode passing through and closely fitting one of said openings and having a projecting foot; journals adjacent the ends of the other opening; insulating washers mounted respectively in said journals; an electrode passing through the opening and held by the washers away 30 from the walls thereof in position to be engaged by the foot of the first electrode, said second electrode having a head at that end adjacent the foot of the other electrode; and means at the opposite end of the second electrode 35 engaging one of the insulating washers to clamp the journals, washers and electrode in place, there being ventilating passages through the outer one of the journals opening into the cavity in which the second 40 electrode is mounted.

In testimony whereof, I have signed my name to this specification, in the presence of two subscribing witnesses.

CLAUDE SPENCER SYDENHAM.
